UNITED STATES PATENT OFFICE.

HENRY KREISINGER, OF PITTSBURGH, PENNSYLVANIA, ASSIGNOR TO COMBUSTION ENGINEERING CORPORATION, A CORPORATION OF NEW YORK.

METHOD OF BURNING PULVERIZED FUEL.

Application filed October 22, 1920. Serial No. 418,640.

To all whom it may concern:

Be it known that I, HENRY KREISINGER, a citizen of the United States, residing at Pittsburgh, in the county of Allegheny and 5 State of Pennsylvania, have invented certain new and useful Improvements in Methods of Burning Pulverized Fuel, of which the following is a specification.

This invention relates to the burning of 10 pulverized fuel and particularly to an improved method of treating and disposing of the slag forming ash and refuse.

It is the specific object of my invention to provide means for treating such ash and 15 refuse during combustion of the fuel in such manner as to prevent their forming into a mass of slag in the bottom of the furnace, difficult if not impossible to remove.

Due to the intense heat prevailing the 20 precipitated ash and refuse generally melt and fuse together to form a mass of liquid slag on the floor of the furnace which cannot readily be removed and which, if permitted to cool, solidifies into a solid cake, 25 which must literally be dug out.

I am aware that it has heretofore been contemplated to overcome these difficulties by cooling the precipitating ash and refuse below slag forming temperature by providing 30 a cooling zone to wit, by a blanket of flowing air below the zone of combustion and through which such products fall to the floor. I propose to overcome these difficulties by mechanical means.

My invention, therefore, contemplates the provision of what may be termed a water screen located in an approximately horizontal or slightly inclined plane at a point 35 a short distance above the floor of the furnace, preferably connected with the circulation of the boiler.

The foregoing, as well as other objects, will be more clearly understood and appreciated in connection with the following description of the accompanying drawings wherein I have illustrated several forms of apparatus suitable for carrying out my improved process, and of which:—

Fig. 1 is a vertical longitudinal section 40 through a steam generating furnace for carrying out my invention taken on the line 1—1 of Fig. 2; Fig. 2 is a front elevation of the construction of Fig. 1; Fig. 3 is a section similar to that of Fig. 1 illustrating an 45 other arrangement for carrying out the in-

vention; and Fig. 4 is a fragmentary section illustrating another form of apparatus suitable for carrying out my invention.

In the showing of Figs. 1 and 2 the combustion chamber A of the steam generating furnace illustrated, which is indicated as a whole by the reference character B, is provided with any desired or suitable form of fuel delivery means or burner C. One or more than one burner may be used and in 55 the present instance I have illustrated two which are located in the upper wall of the combustion chamber at a point somewhat to the rear of the front wall 1. It will be noted that these burners occupy a vertical 60 position as I prefer to introduce the fuel from above and to permit it to drop more or less gently toward the zone in which combustion thereof takes place. The furnace is provided with a suitable outlet 2 for the hot 65 gases and other products of combustion which are drawn off under the influence of the draft and across this outlet opening I provide any suitable or desired arrangement of water tubes 3 for the generation of 70 steam.

Referring to the details of the burner it might be well to point out that the mixture of fuel is introduced through the pipe 4 the flow of which is aided, if desired, by means 75 of a jet of steam or air introduced through the pipe 5. I prefer that this jet, if it be used at all, be not at any time violent as I desire the fuel after it enters the furnace to follow the more or less gentle and natural 80 path through the zone of combustion induced by and under the control of the draft. The burner is also provided with the auxiliary openings or channels 6 and 7 through 85 which additional air may be induced into the combustion chamber. A damper 8 provides a means for controlling the supply 90 admitted through the channel 6.

At various points in the front wall 1 of the furnace are located the auxiliary air inlets 9, regulation of which is secured by means of the damper doors 10. Chain operating means 11 for these doors may be provided if desired. In Figs. 2 and 4 the 100 chains are not illustrated in order to avoid confusion in the showing.

At a short distance above the floor 12 I 105 arrange a plurality of spaced tubes 13 which are inclined slightly from the rear wall 14 to the front wall 1. Below the up-

per ends of the tubes and in the front wall of the furnace are provided two ash or slag removing doors 15.

The following novel arrangement provides a circulation of water through the tubes 13. Extending transversely of the furnace and located in the rear wall 14 thereof is an inlet header 16 which communicates with all of the tubes, and in the front wall of the furnace is located, also transversely of the furnace, an outlet header 17, connecting with the other ends of the tubes. Certain of the usual water tubes 3, preferably those in the outer lower corners, are omitted and are replaced by the pipes 18 leading to the ends of the header 16, and by the pipes 19, connected to the ends of the header 17, the pipes 19 being bent inwardly so as to extend into the upper portion of the combustion chamber.

In Figure 3 is illustrated a modification in which two or more tubes 19^a connect the header 17 with the steam drum, such tubes being located entirely without the furnace.

25 A suitable connection 21 leads to the header 16 from a source of water supply and a feed pump 20 is provided in the line. The pipes 18 in this case, act to protect the apparatus at times when the pump is not in operation.

In the modification of Fig. 4, the header 16 is connected as before to a source of supply and is fed by a pump 20, while a hot water line 22 is connected to the header 17 and leads to any desired point of use. In this form, therefore, the water screen is independent of the boiler setting and is used as a heater in addition to its other functions now to be set forth.

40 As to the combustion chamber and the screen in lower part thereof, the spaces of the screen are sufficiently large to prevent precipitating ash and refuse from closing the same.

45 It will be seen from the foregoing that in all the forms described the ash and refuse which gravitate and such as are carried along with the flames toward the water screen during the burning of the fuel will 50 either strike and lodge on or pass closely adjacent to the tubes of the water bottom.

Such ash and refuse as lodge on the tubes build up somewhat and then, if the surface thereof liquefies, a dripping off may 55 occur. In normal operation, the hammering or vibration in the tubes and the expansion and contraction thereof under different temperatures suffice to loosen such accumulations on the tubes with the result that it 60 is common for the same to drop off. The deposit on the floor is composed of the ash and of the material falling from the tubes and of the drippings, if any, which latter take the form of small particles or nodules.

65 The comparatively cool tubes prevent the

melting or coalescing of the deposit into a solid mass of slag because they absorb the radiant heat of the deposit and maintain the temperature of the deposit at a point below that at which fusion or coalescing takes place and the deposit, therefore, remains a mixture of ash and residue of a character which can be easily removed, the deposit being removed in normal operation and not allowed to build up to a point where it would become fused by the heat.

The tubes act somewhat in the nature of a screen with respect to the progress of the flames downwardly in that the chilling or cooling effect tends to arrest the flames before they reach the bottom. Some tongues of flame may reach the deposit but the temperature, as before pointed out, is maintained at a point preventing appreciable coalescing.

I have illustrated the water screen as composed of a plurality of spaced tubes but it will readily be seen that other means might well be employed. It is essential only that the cooling surfaces of the water screen be interrupted as with openings or spaces and yet arranged to provide a surface continuous enough to produce the desired results, in other words to provide a fluid cooled medium of sufficient capacity and arrangement to prevent appreciable coalescing of the precipitating ash particles and the deposit thereof.

Low grade fuels normally produce great slagging difficulties. It will be apparent that this improved method of treating and disposing of the slag forming ash and refuse makes it possible to successfully utilize fuels of a grade ordinarily too low for practical purposes.

In all the forms, I cut back the side walls to above the tubes to provide an overhanging shoulder or lip 24 from which the slag which is formed on the side walls can drop off either onto or closely adjacent the tubes. These drippings may be of comparatively large size and some of them may coalesce or partly coalesce, but the heat absorbed by the screen is sufficient to prevent the formation of any lumps difficult of removal. This is an important feature of my invention as the formation of slag on the side walls has heretofore presented very troublesome obstacles in the burning of pulverized fuel.

It is well known in the pulverized fuel burning art that the temperature in the combustion is sufficient to fuse the refuse particles of the coal being burned in suspension and these particles in the absence of cooling will collect and run together into a coalesced mass such as previously described. The water screen described herein is a mechanical fluid cooled heat absorbing medium—dependent upon the indirect effect of a fluid cooling medium as water—through which

the precipitating particles pass or are subjected to the influence thereof in a manner to prevent the collection of an appreciable mass of coalesced material; and this screen is arranged between the flame and the surface on which collection or deposit takes place, so that a cooling zone is created which prevents coalescence of refuse particles passing out of the flame and of the deposit there-
 10 of in the protected space intermediate the flame and the recipient surface. It will also be observed that this water screen creates a relatively cool zone towards or through which particles of refuse in the combustion zone travel from the flame and which particles, if not cooled below coalescence by the screen, would lodge on a refractory or other hot surface and form or collect into a runny or flowing coalesced mass or body, and the
 15 cooling by the fluid cooled means for preventing this is an important aspect of my invention.

I claim:

1. The process of burning fuel in a combustion chamber which consists in admitting, igniting and burning the fuel within such chamber, and in creating and maintaining a cooling zone in such chamber, intermediate the flame and a recipient defining
 25 surface of such chamber, through which zone refuse particles leaving the flame in regular substantially continuous operation pass toward such surface and which zone is cooled and maintained cool enough to cool
 30 such refuse particles while in suspension below the point of coalescence by the indirect action of a cooling medium.
 35

2. The process of burning fuel in a combustion chamber which consists in admitting, igniting and burning the fuel within such chamber and in cooling refuse particles passing from the flame in regular normal operation to a recipient defining surface of such chamber while the particles are in sus-
 40 pension in the chamber and in also cooling the deposit thereof in the chamber, down to a consistency at which the particles will not run, by the indirect action of a cooling me-
 dium.

50 3. The method which comprises supplying pulverulent fuel to the interior of a combustion chamber into which combustion supporting air flows, substantially completely burning the fuel while within said chamber, and while the gaseous products of combustion pass from the chamber, and in cooling refuse particles passing from the flame stream during the normal continuous operation toward a surface of such chamber
 55 while they are in suspension in the chamber, by the effect of an indirectly applied cooling medium, below the coalescing tempera-
 60 ture of said particles.

4. The process of burning fuel in a combustion chamber which consists in admitting,

igniting and burning the fuel within such chamber and in cooling refuse particles passing from the flame in regular normal operation to a recipient surface defining such chamber, down to a consistency at which the particles will not run, while they are in suspension within the chamber, by the cooling effect of water in pipes constituting a screen within the chamber.

5. The process of burning fuel in a combustion chamber wherein the fuel is admitted and subjected to substantially complete combustion therein, and in which the refuse particles passing from the flame in normal substantially continuous operation are prevented from forming into a body of liquid on a surface of such chamber by being sufficiently cooled while in suspension within such chamber by the indirect cooling action of a water-cooled heat absorbing screen located in advance of said surface, toward which said refuse travels from the flame.

6. The process of burning fuel in suspension in a combustion chamber in which the refuse particles passing from the flame in normal regular operation toward a surface of such chamber and depositing thereon, are cooled below the point of coalescence by causing such particles during the movement to the place of deposit in the chamber to pass through a cooling zone created by the absorption of heat by the indirect action of a cooling medium, and in removing deposited material before the accumulation thereof is sufficient to defeat a continuance of such cooling.

7. The process of burning fuel in a combustion chamber wherein the fuel is admitted in pulverized form and subjected to substantially complete combustion while in suspension therein at a temperature above the fusing point of the refuse of the fuel, in which the refuse particles precipitating out of the flame in regular operation, deposit in an ash-receiving space below the zone of combustion and are cooled in transit and while still in suspension in the chamber to a temperature at which coalescing into large solid bodies is avoided, by being subjected to the cooling effect of a water cooled screen arranged in the combustion chamber above the point of deposit.

8. The process of burning fuel in suspension in a combustion chamber wherein the fuel is admitted and subjected to substantially complete combustion therein and the refuse particles precipitating out of the flame in regular operation are allowed to deposit within the combustion chamber, in which process the precipitating and precipitated particles are cooled and are maintained cool, below the temperature at which they will fuse, by a heat absorbing medium which cools to the requisite temperature and maintains cooled to the requisite tempera-
 120
 125
 130

ture, the precipitating and precipitated particles, but which cooling medium, during its cooling, does not mix with the products of combustion.

5 9. The process of burning fuel in a combustion chamber, wherein the fuel is admitted, ignited and substantially completely burned therein, in which refuse matter passing out of the flame stream directly to a place
10 of lodgment within such chamber, is cooled

below a point at which a flowing mass thereof can form on the place of lodgment, this being accomplished by cooling and maintaining solid matter cooled, by the indirect action of a cooling medium, below the temperature of coalescence of the refuse particles.

15 In testimony whereof, I have hereunto signed my name.

HENRY KREISINGER.
